US0D1086189S

(12) **United States Design Patent** (10) Patent No.: **US D1,086,189 S**
(45) Date of Patent: ** Jul. 29, 2025

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, Los Gatos, CA (US);
Victoria Elaine Hinn, Brooklyn, NY (US); **Eric Lance Wilson**, San Jose, CA (US)

(73) Assignee: **Apple Inc.**, Cupertino, CA (US)

(**) Term: **15 Years**

(21) Appl. No.: **29/940,823**

(22) Filed: **May 6, 2024**

Related U.S. Application Data

(63) Continuation of application No. 29/909,093, filed on Aug. 1, 2023, now Pat. No. Des. 1,026,026, which is a continuation of application No. 29/807,456, filed on Sep. 12, 2021, now Pat. No. Des. 997,987.

(57)

CLAIM

The ornamental design for a display screen or portion thereof with graphical user interface as shown and described.

DESCRIPTION

The FIGURE is a front view of a display screen or portion thereof with graphical user interface showing the claimed design.

The broken lines in the FIGURE show a display screen or portion thereof, and form no part of the claimed design.

1 Claim, 1 Drawing Sheet
